UNITED STATES PATENT OFFICE.

HOWARD EARL HOOVER, OF CHICAGO, ILLINOIS, ASSIGNOR, BY MESNE ASSIGNMENTS,
TO THE HOOVER COMPANY, OF NORTH CANTON, OHIO, A CORPORATION OF OHIO.

SUCTION SWEEPER.

Application filed October 20, 1919. Serial No. 331,908.

To all whom it may concern:

Be it known that I, HOWARD EARL HOOVER, a citizen of the United States, residing at Chicago, in the county of Cook and State of Illinois, have invented a certain new and useful Improvement in Suction Sweepers, of which the following is a specification.

My invention relates to a combined installed plant and motor driven brush apparatus for suction sweeper. Generally speaking, the object of this invention is to provide means whereby a motor driven and particularly a beating brush or a brushing and beating apparatus motor driven of any kind can be used in and with a nozzle while the suction apparatus associated therewith is placed at a distance, as for example, in a stationary plant in the basement of the building. In the preferred form of my invention, I use a device which has both a beating and a brushing effect and I drive it at a high rate of speed by means of a motor mounted on and associated with the brush nozzle. A flexible conduit leads from the nozzle to the pipe or conduit which connects with the installed or stationary suction plant so that the nozzle can be moved freely about the room where the sweeping or cleaning is to be done. This flexible conduit may connect directly with the nozzle body or as shown in a modified form herewith to a handle or handle portion which is hollow and connected with the nozzle. The first is the preferred form of this application.

In the preferred form of my device, the nozzle is provided with a relatively wide open mouth and this is preferably supported above the floor so that the carpet or floor covering will rise thereto and the mouth will be big enough to furnish a proper field of operation for the beater and the brush or the beating brush. In the preferred form the connection between the handle or handle device is made as shown in front of the center of gravity of the machine and my object in this is to keep the dirt from spilling out of the casing when the machine is lifted from the floor. Another object of my invention is to produce a sweeping appa-

ratus the height of which shall be as low as possible to permit its insertion under articles of furniture and where the handle or combined handle and conduit will be capable of being swung down in the horizontal position below the highest portion of the head.

My invention is illustrated in the accompanying drawings wherein—

Fig. 1 is a plan view with parts broken away;

Fig. 2 is a side elevation;

Fig. 3 is a plan view with parts broken away of an alternative form;

Fig. 4 is an elevation of that form;

Fig. 5 is a detailed section along the line 5—5 of Fig. 3.

Like parts are indicated by like characters in all the figures.

A is a movable suction head having along its front side an enlarged brush chamber A² having a downwardly open wide suction mouth A³ arranged to be held above the floor by the rollers A⁴ adjacent the suction mouth and the adjustable rollers A⁵ removed from the suction mouth. The arrangement is such that adjustment of the rollers A⁵ by rotating the entire suction head about the rollers A⁴ will change the height of the suction mouth or nozzle above the floor. A⁶ A⁷ are brush guard fingers extending across the open mouth to make it impossible for any rug or floor covering to be drawn up too far into the open mouth. The brush chamber A² communicates toward the rear with an enlarged bifurcated suction chamber, the two arms of which communicate with the brush chamber adjacent its two ends and are at the other end, joined and communicate with a hose pipe connection sleeve A⁸. The arrangement is such that the air will be drawn off through a pipe A⁹ communicating with the sleeve A⁸, and because the cross section of the air passage as shown decreases from the nozzle or suction mouth rearwardly toward the sleeve, the suction and velocity at the suction mouth will be less than that in the pipe.

B is a combined beating and sweeping brush, the two separate functions of which

are, by its shape and arrangement, combined in one unit though obviously the beating and sweeping devices might be separated. This brush is rotatably mounted 5 upon a shaft B^1 which shaft is anchored at either end in the housing. B^2 B^2 are thread guards surrounding the ends of the bearings to protect the bearings from fouling. B^3 is a pulley on the brush whereby the 10 belt B^4 which is driven in turn by a pulley B^5 may rotate the brush. B^6 is a removable hand hole cover in the side of the belt housing B^7 whereby access may be had to the pulley B^5 for the purpose of adjusting the 15 pulley B^4 . B^7 is a belt housing and motor support mounted upon and integral with the suction head A. It forms throughout a part of its length a channel separate from the suction head and communicating with it 20 adjacent the brush chamber A^2 but into which the dust laden air is not drawn.

C is a motor enclosed within a casing as indicated. It is located above the passageway through the head and is mounted 25 upon the belt housing B^7 .

In Figure 3 I have shown a modified form in which the belt housing B^7 is of greater width than that shown in the preferred form of Fig. 1 and in which the motor housing is 30 partially enclosed within such housing.

A combined conduit and handle F is substituted for the handle D and conduit A^8 of Fig. 1. The handle F is a hollow handle adapted to be connected at its upper end to 35 a flexible conduit which is in turn connected to the suction system. To provide for motion of the conduit handle, a hose pipe connecting sleeve H is rotatably connected to the two ends of the bifurcated suction chamber. The supporting wheels A⁵ are mounted 40 directly on a rearward portion of the suction head.

The handle stop D² is mounted on the motor housing and upon the conduit handle.

G is the rotatable union of the hose pipe connecting sleeve H and the arms of the suction head and is made up of the lips G¹ on the end of the opposite arms of sleeve H the holding band G² which grips them and the 50 screw G³ which clamps the holding band in position.

J J are a series of holes as here shown diagrammatic but adapted to be arranged in any manner about the motor bearing in the 55 wall of the belt housing. They may or may not be used. Under certain conditions of operation or with certain designs of machines they would be desirable. With others they might be unnecessary. They would admit air about the motor bearing and develop 60 a current of air toward the brush through the brush chamber and thence through the rearwardly extending part thus keeping the belt housing chamber free from dust and the 65 bearings protected from dust.

Without such holes the bearing is in a pocket in which there is little if any tendency for dust laden air or particles of dust or material to penetrate.

K is the motor socket or base casting. It 70 may be part of the general housing casting or it may be secured in position on the general housing casting as for example, the screws K¹ K¹. It carries at its outer end, a cap frame or head casting K² in which the 75 shaft of the motor is supported. One bearing of the motor shaft is carried by the cap frame K² and the other by the base casting or socket K. K³ is a cap which surrounds the end of the motor and the cap frame. 80

The use and operation of my invention are as follows:—

When the machine is put into operation the dust laden air is drawn through the nozzle brush chamber rearwardly projecting 85 part and out through the conduit in the usual way. The motor is let down upon the downwardly bent portion of the rearwardly extending part so that it occupies the least

possible space so that the apparatus should 90 be relatively low. The bifurcated device in the rearwardly extending portion when used can be designed so as to insure a practically uniform movement of air along the length of the brush. If the belt housing is associated 95

with the motor pocket, the motor can be very easily attached in position and held there, it only being necessary to remove it or put the cap in position to secure the motor in place. The belt housing chamber has 100 little if any tendency to accumulate or receive dust laden air and when the design is such as to permit it, the holes about the motor shaft will admit enough air to keep the bearing and the belt housing clean. Where 105 the handle and conduit are one and the same, it is necessary that the handle conduit should be pivotally attached to the frame or casing.

I claim:—

1. A suction sweeper comprising a casing 110 having a nozzle provided with an inlet and a conduit in combination with a carpet agitating device mounted near the inlet, a motor supported on the conduit, a driving connection from the motor to the carpet agitating device and a housing to receive a portion 115 of such driving device, said housing forming a part of the motor support, said conduit downwardly depressed between the nozzle and the outer end to make room for the 120 motor.

2. A suction sweeper comprising a casing having a nozzle provided with an inlet and a conduit in combination with a carpet agitating device mounted near the inlet, a motor supported on the conduit, a driving connection from the motor to the carpet agitating device and a housing separate from said 125 inlet and conduit to receive a portion of such driving device and forming a part of the mo- 130

tor support, said housing provided with a hand hole and a removable cover for said hole in the side of the housing opposite the end of the motor, said conduit being flattened between the nozzle and the outer end to make room for the motor, said conduit being bifurcated.

In testimony whereof, I affix my signature in the presence of two witnesses this 13th day of October, 1919.

HOWARD EARL HOOVER.
